Application May 12, 1931, Serial No. 536,733

6 Claims. (Cl. 209—44)

This invention relates to separation apparatus for use in the preparation of coal, coke, minerals and the like and has for its object the provision of an apparatus and method for effecting a separation of any of the aforementioned from its associated impurities in a minimum of space, time and operation.

Another object is to provide concentrating or cleaning apparatus of a general construction which renders it usable with either a water or an air medium with but little modification.

Another object is to provide a device of this kind comprising a pair of cooperating decks arranged in series, or tandem, of novel construction wherein a primary deck is provided with a superimposed separating screen, the object of which is to separate the finer materials from the coarse materials. The finer materials thus separated fall to the primary deck where they are cleaned and passed to the secondary deck on which they assist in cleaning the coarser materials. This arrangement dispenses with the elaborate apparatus heretofore necessary to obtain an efficient cleaning.

These and other objects are attained by the means described herein and disclosed in the accompanying drawings, in which:

Fig. 1 is a side elevational view of the device of the invention.

Fig. 2 is a view taken on line 2—2 of Fig. 1, part being broken away.

Fig. 3 is a view of the device taken on line 3—3 of Fig. 1, part being broken away.

Fig. 4 is a plan view of a control device forming a detail of the invention.

Fig. 5 is a perspective view of a riffle member forming a detail of the invention.

Fig. 6 is a top plan view of a modified form of deck for the device.

Fig. 7 is a sectional view on line 7—7 of the deck shown in Fig. 6.

Fig. 8 shows diagrammatically, in side elevation, an electrically operated deck of the suspended type.

Fig. 9 is a detail view of a buffer of the invention.

Fig. 10 is a view taken on line 10—10 of Fig. 3.

Ores, coal, etc., are usually contaminated with impurities, and it is necessary to separate the desired substance from the contaminating substances before putting it to its intended use. Heretofore known cleaning and classifying apparatus has usually been of rather large dimension and has often consisted of a number of separate

units. The use of vibrating or reciprocating decks is, broadly speaking, old practice.

The hereinafter described apparatus entails the use of a relatively compact arrangement of short decks having a more efficient riffle structure than previously used and operating, together with other instrumentalities in effecting a complete separation of coal or other substance in a single operation.

In the present embodiment, the device of the invention comprises a suitable air chamber 10 fed through inlet pipe 11 from any suitable source of air under pressure (not shown). Mounted at each longitudinal side of the air chamber or chest 10 is a pair of longitudinally extending members such as structural channels 12 which also carry the reciprocating mechanism employed for the separator. The reciprocating mechanism may consist of a power source such as motor M which drives shaft 14 through any suitable mechanism such as pulleys 15 and belt 16 and which carries a pair of eccentrics 17 and a second pair of eccentrics 18. A primary or short deck 19 is supported upon a pair of toggle links 20 and reciprocating motion is imparted thereto by a pitman 21 connected to the deck 19 and the eccentrics 18. The deck has a hollow box-like frame over which extends the deck proper which may have a trough-like cross sectional shape such as is shown in Fig. 2, or any other approved cross sectional design. The cross section of each of the decks being of somewhat similar construction, reference is made to Fig. 2 for structural details. The side pieces 22 are solid and imperforate and are supported by the pairs of toggle links 20 so that the reciprocating movement of pitmans 21 and 210 effect longitudinal reciprocation. The discharge end of the first table is disposed at a higher elevation so that the material discharged therefrom may be dropped onto the second table. Each deck has a series of ribs 23 extending laterally from the sides 22 to adjacent longitudinally extending stringers 24, the space between said stringers having a plurality of tiltable louvres 25 which are controllable to vary the direction of air under pressure moving upwardly from the interior of air chest 10. Mounted over the upper surface of the ribs and across the top of the movable louvres is a perforated covering of wire cloth 100 or its equivalent upon which is mounted a series of riffles 26 outwardly diverging and each having a series of angular offsets intermediate its ends as at 27, 28 and 29. On the underface of the ribs 23 is a series of air control panel structures for example as shown in Fig. 4, which

may be provided in a simple manner by employing superposed perforate sheets 30 and 31 shiftable to control the quantity of air under pressure passing from the chamber 10 into space 32 above the decks.

With the use of air under pressure there is employed a dome-like screen 33 which retards the escape of air after its passage through the air control panels 30-31 and tends to create a static pressure immediately above the top of the deck.

Fixed at a distance above the primary deck, and beneath dome 33, is a screen 34 onto which coal or other material is poured through feed chute 35. The secondary deck 36 constructed substantially as previously described has a flexible air-tight connection 37 with the deck 19 to preclude loss of air pressure beneath the deck. A dome-like screen or mesh cover 330, similar to the cover 33, extends over the secondary deck and is flexibly connected as at 38 with the cover 33. The pitmans 210 impart a longer stroke and a relatively different speed of reciprocation to the secondary deck 36 than that imparted to the primary deck by the pitmans 21. The difference in length and speed of stroke of the pitmans may be accomplished by any suitable means such as by having the respective pitmans operative on different diameter eccentrics or any other known manner. Interiorly of the dome-like covers 33-330 the primary deck 19 has an overhanging lip 39 which allows the products from the primary deck to spill onto the riffled top of the secondary deck. Here the riffles 260 are again provided with angles such as at 270 and 280.

If desired the decks can also be set into reciprocating motion by means of electrical vibrator arrangements, the decks being suspended in a yieldable and reciprocable fashion from an overhead beam. This is shown diagrammatically in Fig. 8.

The vibrators 80 are electrically operated and may be of any approved type obtainable on the market. Wires 81 connected to a source of electrical supply are used to actuate these vibrators.

Buffers such as 40 and 41 are placed in relatively symmetrical pairs at opposite sides of the secondary deck.

Buffers 40 may be solid obstructions at the side of the deck, against which the heavy material piles up and spills off through the openings or ports 45 in screen dome 33-330. Buffers 41 may have longitudinally extending ways emptying through ports 45 which extend through the end wall 331 and these ways have floating gates 410 on the lateral inside faces. See Figs. 3 and 9.

A substantially triangular dividing wedge 42 is mounted on top of the screen 34.

From the foregoing it will be apparent that air under pressure passing upwardly between the louvres 25 and through the air controls 30-31 will pass upwardly through the perforated cover between the riffles 26 so that materials such as coal to be cleaned will be subjected to controlled degrees of velocity air movement at different points along the length of the structure accordingly as the air control plates may be adjusted. At the same time longitudinal reciprocation of the decks assist the spilling of the lighter particles over the tops of the riffles 26. The maintenance of a static air pressure above the deck and below the screen-like dome effects a quicker and more effective separation of the heavier and lighter particles.

As was heretofore intimated the structure just

described is not limited to the use of air as a medium of floatation.

Where large quantities of water are chiefly available it is possible to pump water upwardly through the chamber 10 and in controlled degrees 5 through the control plates 30-31 and between the louvres 25 for operating upon the coal or other material during the vibratory movement of the decks. In this construction the fine wire mesh dome or cover 33-330 may be omitted. 10

The operation of the device with water as a floatation medium is as follows. The water is pumped upwardly through the chamber as just described and the coal or other material is continuously dumped into feed chute 35 onto screen 15 34 where an initial sizing of material takes place. The smaller material passes through the screen onto the riffles of primary deck 19 where, due to the outward divergence of curved riffles 26, the efficiency of which is especially augmented by the occasional angles such as 27-28 and 29, the lighter particles are moved forwardly over the tops of the riffles and the heavier particles are shunted laterally by the curved riffles and the angles therein. 24

The larger materials which have not passed through screen 34 are moved forwardly over said screen due to the reciprocatory movement of the deck and screen and are shunted sidewardly by the wedge shaped lock 42 on the screen. These 30 larger particles therefore, when they reach the forward end of the screen will drop directly onto the outer sides of the secondary deck 36 where they will be acted upon by the curved riffles 260, the efficiency of which is augmented by the occasional angles 270-280, etc. The smaller particles on the primary deck undergo a very thorough separation on the primary deck. The incoming rush of water tending to separate particles which might tend to adhere if the material 40 entering the chute 35 is wet.

The buffers 40 discharge the heavier materials which are entrapped by the outermost riffles 260 at intervals along opposite sides of the members 43. 45

It is to be understood that the control panels 30-31 would be arranged to provide an increasing pressure from feed end to discharge end.

The louvres 25 would be adjusted so that the inflow of the floatation medium would oppose the advance of the material, thereby affording every opportunity for the heavier particles to shift laterally of the center and thus afford an increasingly perfected stratified bed of material as the general forward movement of said material approaches the discharge end 44. 55

Describing the operation of the device arranged for the use of air as a floatation medium, it is to be understood that the fine meshed dome-like covers 33-330 would be employed and that air under pressure would be constantly charged into the air chamber 10. This arrangement is especially desirable when the material to be cleaned is coal or coke. The material is continuously poured into the charging chute 35 65 and onto the screen 34 where the larger particles are immediately separated from the smaller, much of the finer material in a state of adhesion due to moisture being separated at this point. A lower velocity pressure is supplied at the feed end 70 so that even the small particles will pass through screen 34 onto deck 19. Here the riffles 26 shunt off the heavier materials while the relatively low pressure is assisting the lighter particles to spill over said riffles toward the center. This partially 75

stratified mass of material continually spills onto the secondary deck while the larger particles which did not pass through the screen 34 are dumped onto the top and onto the mass. Refuse ports 45, which are openings in the dome screens 33—330, may be provided closely adjacent the baffles 40 and 41 to permit the larger heavy masses to spill over the side members 43. The refuse ports 45 in dome screen 33 permit discharge of some of the heavy material therethrough from the first deck, the heavy material being disposed of wherever possible by spilling them from the sides of the reciprocating decks. The closely meshed domes 33—330 and screen end wall 331 trap the air and prevent its rapid escape and also create a small amount of back pressure which retards the incoming air. This condition therefore affords a sort of static pressure which is especially effective in separating fine particles from heavier while the light group are in suspension.

It is to be understood that while the deck apparatus is shown to be substantially rectangular, this particular arrangement is not vital, since it may well be changed to a general elliptical shape if desired. The riffle decks as shown are of substantially trough-shape but may be made substantially convex as illustrated in Figs. 6 and 7. In this embodiment it would be understood that the angle of the riffles would be reversed with a tendency toward convergence at the center and discharge end. By providing the series of independent air control plates along the length of the device it is possible to subject the freshly received materials to lesser velocity pressure so that the very fine particles will not be blown entirely out of the device, but will take the course centerward to build up a heavier stratified bed which can be operated upon by increasing velocity pressure as the entire mass approaches the discharge end.

It is to be understood that the operation of the device may be substantially continuous and that in the cleaning of coal, a partial classification as to size is effected along with the cleaning.

What is claimed is:

1. In a separating device for coals, ore and the like, the combination of a primary deck and a secondary deck, curved riffles on said decks, the primary deck being disposed at a higher elevation than the secondary deck and having an overhanging edge, a single power means and effecting vibration of the decks at different speeds, a screen deck carried by and overlying the primary deck, a charging chute above said screen deck and flexibly connected air retarding covers mounted over said decks.

2. In a separation apparatus the combination of a primary riffle deck, a separating screen carried by and disposed above said primary deck, a secondary riffle deck, the forward edge of the primary deck and screen overhanging said secondary deck, and means for effecting vibration of said decks at different rates. 5

3. In a device of the class described the combination with a deck structure having riffles on its upper face, of a series of air control panels mounted along the length of said deck at each side, each air control panel comprising a pair of superposed perforate members arranged for shiftable relative adjustment and fixation in adjusted positions and a central longitudinal series of 15 louvers between said series of air control panels. 10

4. In a device of the class described the combination of a deck substantially trough-shaped in cross section, said trough having a horizontal bottom, transverse louvres in said bottom, angularly inclined sides extending from said horizontal bottom; divergent sets of curved riffles arranged in spaced relation over said sides and bottom on the upper faces thereof and independent sectionally adjustable air volume control members disposed at opposite sides of said louvers and beneath the inclined sides. 20

5. In a device of the class described the combination of a pair of riffle decks comprising a primary deck and a secondary deck, a separating screen mounted above and carried by the primary deck, a wedge shaped buffer on the discharge end of said screen, the decks being flexibly connected at adjacent ends and arranged in such relation that material passing through the screen may be treated on the primary deck and discharged onto the secondary deck for further treatment, the material on the said screen being discharged onto the pre-treated material on the secondary deck, means effecting reciprocation of said decks at different speeds and means providing a varying flow of a floatation medium upwardly through both of said riffle decks. 30

6. In combination a pair of riffle decks each having a discharge end and a receiving end, one 45 of said decks having its discharge end disposed over the receiving end of the other, a separating screen member disposed over the elevated deck and having an end discharging onto the second deck, a separating wedge carried by said separating 50 screen, electrical vibrating means carried by each deck to impart movement thereto, and means for directing a floatation medium upwardly through said decks.
